U.S. Cl. D12—102

FIG. 1.

FIG. 2.

FIG. 3.

FIG. 4.

FIG. 1 is a side elevational view of a mobile diner embodying my new design, the opposite side being substantially a mirror image thereof;

FIG. 2 is a rear elevational view with the steps in folded position for travel;

FIG. 3 is a front elevational view showing the steps in position as in FIG. 1;

FIG. 4 is a front elevational view thereof with portions of the forward panel broken away to show the steps in folded position for travel.

The letters and numerals shown in broken lines in FIG. 1 are for illustrative purposes only.

I claim:

The ornamental design for a mobile diner, substantially as shown, and described.
